ELECTRIC CIRCUIT BREAKER

Filed March 8, 1934

FIG. 1.

FIG. 2.

Inventor:
Harold E. Strang,
by Harry E. Dunham
His Attorney.

UNITED STATES PATENT OFFICE

2,050,864

ELECTRIC CIRCUIT BREAKER

Harold E. Strang, South Ardmore, Pa., assignor
to General Electric Company, a corporation of
New York

Application March 8, 1934, Serial No. 714,561

6 Claims. (Cl. 200—87)

My invention relates to electric circuit breakers, more particularly to means for positioning and mounting the operating mechanism with respect to the main circuit breaker housing.

5 Heretofore it has been the usual practice in manufacturing and assembling oil circuit breakers to design two separate units, namely, the oil circuit breaker proper and the operating mechanism therefor, and to assemble these units as 10 by bolting to a common frame or interconnecting structure. This arrangement necessitates the use of additional cranks and interconnecting links for the circuit breaker and operating mechanisms, requires an appreciable amount of space and is 15 generally awkward in appearance.

A principal object of my invention is the provision of an improved circuit breaker structure wherein the circuit breaker and operating mechanism therefor comprise a compact, simple and 20 rugged unit.

25 My invention will be more fully set forth in the following description referring to the accompanying drawing, and the features of novelty which characterize my invention will be pointed out with particularity in the claims annexed to and forming a part of this specification.

Referring to the drawing, Fig. 1 is a perspective view illustrating an oil circuit breaker embodying the present invention with the oil tank 30 for the contact structure removed, and Fig. 2 is an elevational sectional view of the complete oil circuit breaker.

The circuit breaker illustrated by Figs. 1 and 2 comprises in general a housing including an oil tank 1 and a cover member or dome 2 in which the relatively movable contact structure 3 is disposed. Operatively connected to the contact structure within the circuit breaker housing and carried by the cover structure is a solenoid operated mechanism 4. The operating mechanism is 35 connected in a manner hereinafter described to the movable contacts or bridging members 5 so as to cause vertical reciprocal movement thereof with respect to the coacting stationary contacts 6.

40 The circuit breaker contact structure forms no part of the present invention, and as illustrated, may be of the well known oil-blast type wherein the relatively movable contacts which are immersed in oil contained in the tank 1, separate 45 within a pressure chamber 7. A side wall 8 of the pressure chamber 7 is provided with a relief opening 9 for each phase disposed opposite one of the breaks so that the arcing pressure generated within said chamber causes a blast of oil across 50 said break and through the relief opening. The

lead-in conductors 10 connected to the stationary contacts 6 are mounted in insulating bushings 11 which are mounted in and extend through the dome 2.

5 The solenoid operating mechanism 4 and the dome 2 are constructed so as to comprise a substantially unitary structure which is very compact and eliminates all cranks and linkages other than those normally required for effecting a circuit closing operation. To this end the dome 2 is provided with a horizontal plate-like flange 12 forming a lateral extension 12' which is the main support for the actuating solenoid 13 of the operating mechanism. The dome 2 has likewise integrally secured thereto, as by welding, a pair 15 of spaced plate-like members 14. The plates 14 which are arranged substantially parallel with respect to each other are vertically positioned above the extension 12' and are welded thereto as indicated at 14'. As illustrated by Fig. 2, the 20 plates 14 are disposed at opposite sides of a pocket 2' formed in the side of the dome 2 and serve as means for mounting and positioning the linkage structure 15 of the operating mechanism.

25 The operating mechanism per se may be of any suitable type and by way of example, there is illustrated the type of solenoid operating mechanism specifically disclosed and claimed in Thumin Patent 1,827,626 for Switch operating mechanism, granted October 13, 1931. The solenoid itself 30 comprises a coil 16 and plunger 17 having an extension 17' for engaging the linkage structure 15. The magnetic circuit of the solenoid comprises a base member 18, a cylindrical shell 19 and the extension 12' which is abutted by the shell 19, the 35 aforesaid elements of the magnetic circuit being of course of suitable magnetic material. The solenoid is suitably suspended beneath the extension 12' as by bolts 20 coacting with the extension 12' and base plate 18.

40 The linkage structure 15 which is mounted above the extension 12' and between the plates 14 comprises a thrust transmitting toggle 21, a tripping toggle 22 coacting with a trigger 23 and trip coil 24 and a prop 25 mounted so as to engage 45 a roller 26 connected to the toggle 21 for maintaining said toggle rigid. The linkage 21 is connected to a double-arm crank 27 pivoted as at 28, the shaft comprising the pivot 28 mounted in and extending through the plates 14 as illustrated by 50 Fig. 1. Openings 29 are provided in the plates 14 for the free end of the crank 27 and the pin 30 which connects the same to the linkage structure 15.

55 The linkage within the circuit breaker dome for

effecting reciprocal vertical movement of the lift rods 31 of the movable contacts may likewise comprise any suitable arrangement, as a linkage 32 connected to the other arm of the crank 27 5 for imparting substantially straight-line movement to the lift rod 31. A piston arrangement 33 subject to the pressure within the chamber 7 is connected as by a link 34 to the aforesaid linkage for imparting an accelerating force to the 10 mechanism upon opening of the circuit.

Accordingly, as clearly illustrated by Fig. 1, the complete circuit breaker mechanism including the relatively movable contact structure and the operating means therefor forms with the dome 15 member a simple, rugged and compact unit.

It should be understood that my invention is not limited to specific details of construction and arrangement thereof herein illustrated, and that changes and modifications may occur to one 20 skilled in the art without departing from the spirit of my invention.

What I claim as new and desire to secure by Letters Patent of the United States is:

1. An electric circuit breaker comprising relatively movable contact structure, a housing therefor including a cover member having a flange-like horizontal portion forming an extension laterally of said cover member, spaced members secured to said extension and said cover member 30 and forming a unitary structure therewith, and operating mechanism for said contact structure in part depending from said extension and in part mounted between said spaced members.

2. An electric circuit breaker comprising relatively movable contact structure, a housing therefor including a dome cover member having a horizontal flange-like lateral extension, spaced substantially parallel plate-like members secured to said dome member and positioned above said extension and forming therewith an integral structure, and operating mechanism for said contact structure carried by said cover member, said operating mechanism in part depending from said extension and including linkage structure mounted in and positioned between said plate-like members.

3. An electric circuit breaker comprising rela-

tively movable contact structure, a housing therefor including a dome cover member, said dome member having a horizontal flange forming an extension laterally of said dome member, spaced substantially parallel plate-like members secured to said dome member and said extension and forming therewith an integral structure, and operating mechanism in part depending from said extension and mounted in part between said plate-like members.

4. An electric circuit breaker comprising relatively movable contact structure, a housing therefor including a cover member, said cover member having a horizontal plate-like extension, and operating mechanism, said mechanism including a solenoid supported by and depending from said extension, and linkage structure mounted above said extension operatively connected to said contact structure.

5. An electric circuit breaker comprising relatively movable contact structure, a metallic housing therefor, a horizontal plate-like extension composed of magnetic material integrally joined to a portion of said housing, an operating mechanism including an actuating solenoid operatively connected to said contact structure, said solenoid having a housing of magnetic material supported by and mounted beneath said extension plate in abutting relation so that said plate forms with said solenoid housing a portion of the magnetic circuit of said solenoid.

6. An electric circuit breaker comprising relatively movable contact structure, a housing therefor including a dome cover member, said dome member provided with a horizontal plate-like extension integrally joined thereto, spaced substantially parallel plate-like members integrally joined to said dome member and said extension, operating mechanism including an actuating solenoid supported by and depending from said extension, and linkage structure operatively connected to said solenoid and contact structure mounted above said extension and between said plate-like members, said plate-like members providing bearings for said linkage structure.

HAROLD E. STRANG.
